UNITED STATES PATENT OFFICE

AUGUSTE J. FONDEVILLE, OF WEST HOBOKEN, NEW JERSEY, ASSIGNOR OF
ONE-HALF TO HARRY VAN IDERSTEIN, OF NEWARK, NEW JERSEY.

DESIGN FOR A DISH OR PLATE OR SIMILAR ARTICLE.

SPECIFICATION forming part of Design No. 36,243, dated March 10, 1903.

Application filed February 5, 1903. Serial No. 142,097. Term of patent 3½ years.

To all whom it may concern:

Be it known that I, AUGUSTE J. FONDEVILLE, a citizen of the United States, residing at West Hoboken, in the county of Hudson and State of New Jersey, have invented and produced a new, original, and ornamental Design for a Dish or Plate or Similar Article, of which the following is a specification, reference being had to the accompanying drawing, forming a part thereof, and in which is illustrated a top view of a dish or plate bearing and incorporating my design.

The leading feature of my design consists of the ornate configuration upon the rim of the dish or plate, substantially as shown.

In the drawing, A designates the body of the dish or plate, and B the rim thereof.

The rim B bears a coat of arms C, the band of ornamental scrollwork D, and the encompassing ornamental band E.

What I claim is—

The ornamental design for a dish or plate or similar article, substantially as shown and described.

Signed at New York, in the county and State 25 of New York, this 3d day of February, A. D. 1903.

AUGUSTE J. FONDEVILLE.
